JOHN McMILLAN, OF CLINTON, BRITISH COLUMBIA, CANADA.

AUTOMATIC GATE-OPENING MECHANISM.

1,076,139.

Specification of Letters Patent.

Patented Oct. 21, 1913.

Application filed September 14, 1911. Serial No. 649,291.

To all whom it may concern:

Be it known that I, JOHN McMILLAN, citizen of the Dominion of Canada, residing at Clinton, in the Province of British Columbia, Canada, have invented a new and useful Automatic Gate-Opening Mechanism, of which the following is a specification.

This invention relates to a mechanical means for opening a gate as that gate is approached by a vehicle, without the inconvenience of one having to dismount from the vehicle to open and close the gate.

The gate cannot only be opened in advance of a vehicle approaching it but is operable automatically by the vehicle itself during that approach, and is similarly automatically closable.

The invention is particularly described in the following specification, reference being made to the drawings by which it is accompanied, in which:

Figure 1 is a plan of the gate and its operating mechanism. Fig. 2, a longitudinal sectional elevation of the same, looking toward the hinge of the gate, and Fig. 3 is an end elevation of the latch lever.

In these drawings 2 represents the line of the road, to which the gate 3 is applied, 4 being the hinge post on which the gate is hung and 5 the latch post to which it is retained in the closed position. The hinge member 6 of the gate is mounted in bearings 7 secured to the gate post 4. The frame of the gate 3 is secured to its hinge member 6 so as to move pivotally with it in the bearings 7 on which it is hinged to the gate post, and on this hinge member 6 is secured a pinion 10 the teeth of which mesh with those of a segment 11 pivotally mounted at 12 to the hinge post 4 of the gate. To the middle of this segment 10 is connected at 13 a rod or wire 14 from the operating mechanism which is on each side of the gate, so as to be operable from either direction. The other end of this connection 14 is attached at 15 to the end of a lever 16 secured in a trough or channel 18 beneath the level of the roadway. To open the gate 3 in a direction away from the approaching vehicle this lever 16 must be moved in the opposite direction, or away from the gate, and as the mechanism is intended to be automatically operated by the vehicle approaching, the rocking shaft 17 on which the lever 16 is secured is operated from a supplementary

rocking shaft 21 on which the vehicle engaging lever 20 is secured, and the shaft 17 is moved from 21 by intermeshing pinions 22 secured on each. By this means, as a vehicle approaches the gate, some part of its under frame will engage the lever 20 and in moving it over toward the gate the movement will be reversed to the rocking shaft 17 and the geared segment 11 will be drawn from the gate to swing the gate 3 open away from the approaching vehicle.

The rocking shaft 17 extends across the width of the road and a lever 25, similar to 16, is secured on its opposite end, connection being made from it by a rod or flexible connection 26 to the lower end of the latch lever 28 which is pivotally mounted at 29 on the latch post 5. The latch lever at its upper end is provided with a notch 30 to receive the latch bolt 31 which is pivotally mounted on the gate. Thus as the movement of the lever 16 rotates the pinion 10 to open the gate the same movement of the rocking shaft 17 draws back by means of the lever 25 the lower end of the latch lever 28 and projects forward the upper end, which retains the latch, thus giving the free end of the gate an impetus in the direction of movement and at the same time turning the latch detent into a position from which the latch may free itself as the gate swings open. After the vehicle has passed through, the gate must in a similar manner be automatically returned to the closed position. This is effected by a closing lever 31 mounted on a rocking shaft 32 extending across the width of the roadway and having a lever 33 secured on it at each end. The ends of these levers 33 are connected by rods 34 to the corresponding ends of the levers 15 and 25 respectively.

The same mechanism for operating and closing is on each side of the gate so that the gate is automatically operable both for opening and closing from either direction of approach.

As a vehicle approaches the gate, when closed, some part of the vehicle underframe, which, if necessary, may be specially designed for the purpose, will engage the lever 20 upwardly projecting from the road surface, and will move it to open the gate. After passing through the gateway the same projection of the vehicle frame will engage the lever 31 and will move it to close the gate.

Having now particularly described my in-

vention and the manner of its operation, I hereby declare that what I claim as new and desire to be protected in by Letters Patent, is:

- 5 1. As a means for automatically opening a gate by the movement of an approaching vehicle, said means comprising, the combination with a gate hinged to open to either side from a mid-position across the road-way, of a pinion secured on the hinge post of the gate, a wheel segment pivotally mounted on the hinge post of the gateway the teeth of which segment mesh with those of the pinion, a rocking shaft mounted on each side 10 of the gate in the line of the roadway said shafts being beneath the level of the road, a lever secured to each shaft and connected to the wheel segment on the post of the gateway below the fulcrum of said wheel segment, a second shaft on each side of the gate and in driving connection with the first named shaft, said second shaft having means secured to it and projecting above the level of the road surface that will be 15 engaged by an approaching vehicle and moved toward the gate to open it, and means on each side of the gate for engaging a vehicle moving from the gate and operating the mechanism to close the gate.
- 20 2. In a device for the purpose specified, the combination with a gate hinged to open to either side from a mid-position extending across a road or railway track, a pinion secured on the hinge post of the gate, a wheel segment pivotally mounted on the hinge post of the gateway, the teeth of which segment mesh with those of the pinion, a rocking shaft supported beneath the road bed on each side of the gate, a lever on each shaft 25 the end of which is connected to the wheel segment below the fulcrum of said wheel segment, a second rocking shaft on each side parallel to the first and in driving connection with it said second shaft having secured 30 to it an operating lever projecting above the surface of the road and designed to be engaged and moved by a vehicle passing over it.
- 35 3. In a device of the class described, the combination with a gate, hinged to open to either side from a mid-position extending across the road, a pinion secured to the hinge post of the gate, a wheel segment mounted

on the hinge post of the gateway, the teeth of which segment mesh with those of the pinion, a latch lever pivotally mounted on the latch post of the gateway the upper end of which latch lever is provided with a detent to retain the latch of the gate, a rocking shaft extending across the road beneath the level of its surface at a distance from the gate on each side of it, each rocking shaft having a lever secured at each end, means for connecting the levers respectively to the wheel segment on the hinge post and to the latch lever on the latch post of the gateway, means projecting above the road surface for engaging an approaching vehicle and rocking the shaft to move the wheel segment and latch lever, and similar means on the opposite side of the gateway for moving the wheel segment and latch lever in the opposite direction.

4. In a device of the class described, a gate hinged to open to either side of a mid-position extending across the road, a pinion secured to the hinge axis of the gate, a wheel segment mounted on the hinge post of the gateway to mesh with the pinion, a latch lever having a detent, a latch on the gate co-operating with said detent, receptacles at each side of the gate in the longitudinal direction of the road and set into the ground, two rocking shafts mounted in each receptacle, levers mounted on each of said rocking shafts, rods connecting the levers of said rocking shafts to said wheel segment and to said latch lever, an operating lever mounted on one rocking shaft in each receptacle and projecting above the plane of the roadway, supplemental shafts mounted in said receptacles and gear connected with the other of the rocking shafts, and a lever mounted on each of said supplemental shafts and also projecting above the roadway, all being arranged substantially as shown and for the purposes described.

In testimony whereof I have signed my name to this specification in the presence of two subscribing witnesses.

JOHN McMILLAN.
